G. H. WHEARY,

JOINT CONSTRUCTION FOR TRUNKS, BOXES, AND THE LIKE.
APPLICATION FILED JULY 21, 1915.

1,314,554.

Patented Sept. 2, 1919.

UNITED STATES PATENT OFFICE.

GEORGE HENRY WHEARY, OF RACINE, WISCONSIN.

JOINT CONSTRUCTION FOR TRUNKS, BOXES, AND THE LIKE.

1,314,554.

Specification of Letters Patent. Patented Sept. 2, 1919.

Application filed July 21, 1915. Serial No. 41,050.

To all whom it may concern:

Be it known that I, GEORGE HENRY WHEARY, a citizen of the United States, and resident of Racine, in the county of Racine and State of Wisconsin, have invented new and useful Improvements in Joint Constructions for Trunks, Boxes, and the like, of which the following is a description, reference being had to the accompanying drawings, which are a part of this specification.

My invention has relation to improvements in joint constructions for trunks, boxes and the like.

When the covers of trunks, boxes and the like are turned to closing position, it is very desirable that the meeting edges of the sides of the body and cover of the trunk or box shall have a joint connection which will secure such a closure as to reduce to the minimum the danger of the entry of dust, or other extraneous matter, to the inside of the trunk.

Wardrobe trunks, as is well known, are composed of two sections, viz., a wardrobe section and a drawer section, one section acting as a cover and being brought against the other section when the trunk is closed. It is obvious that it is as equally desirable in this form of trunk to also provide for a joint which will practically exclude dust, and other extraneous matter. In the present illustration of my invention, I have shown the improvements as applied to a wardrobe form of trunk; although it is of course to be understood that the invention is equally applicable to any form of trunk, box or receptacle which is provided with a closure or cover.

An important object of the invention is to provide a simple form of joint structure, involving a joint closure which will most effectively render the trunk proof against the entry of dust or other matter through the joint to the interior of the trunk or receptacle.

A further object is to provide a form of joint which will not only act to strengthen and brace the trunk, but which will also hold the two sections of the trunk or the body of the trunk or cover thereof, when closed, firmly together against movement one upon the other.

With the above primary, and other incidental objects in view, the invention consists of the devices and parts, or the equiva-

lents thereof, as hereinafter more fully pointed out.

In the accompanying drawing,

Figure 1 is a front elevation of a wardrobe trunk, the two sections thereof being swung outwardly to open position;

Fig. 2 is a fragmentary view, illustrating one corner of the wardrobe section and one corner of the drawer section of the trunk;

Fig. 3 is a horizontal section on the line 3—3 of Fig. 2, looking downwardly in the direction of the arrows, when the wardrobe section and the drawer section are in closed position, the dotted line indicating the position of the wardrobe section relative to the drawer section when the said two sections are in open position;

Fig. 4 is a horizontal section on the line 4—4 of Fig. 2 looking downwardly in the direction of the arrows; and

Fig. 5 is a horizontal section on the line 5—5 of Fig. 2 looking downwardly in the direction of the arrows.

Referring to the drawing, the numeral 6 indicates the wardrobe section and 7 the drawer section of a form of wardrobe trunk.

The principal feature of the invention is the provision of a valance, preferably of metal, said valance disposed around the edges of the sides of one of the sections of the trunk and being formed with a U-shaped portion which provides a groove or pocket to receive the edges of the sides of the other section, and also to receive and hold a felt strip. I prefer to form this member from a single piece of metal which is bent and doubled upon itself to form the portion 8 comprising two thicknesses, and is then bent inwardly at right angles to form the portion 9, and is finally bent at right angles to the portion 9 to form an inner portion 10 which extends in the direction of the portion 8, the portions 8, 9 and 10 being so disposed and arranged with respect to each other as to form a groove or pocket. From the doubled portion 8 the upper thickness of the metal projects or extends to form the part 11.

The joint structure above described may be secured to the outer edges of the sides of either the wardrobe section or the drawer section of a wardrobe trunk. In the accompanying drawing, I have shown the same as secured to the edges of the sides of the wardrobe section, and in the case of an or-

2
dinary form of trunk which merely consists of a main body portion and a cover portion, this joint structure can also be secured to the edges of the sides of either the body or

5 cover.

Assuming that the joint structure described is to be connected to the drawer section of a wardrobe trunk, or in the case of an ordinary trunk to the cover thereof, the 10 metal fixture is adjusted to the outer edges of the sides of said wardrobe section or cover with the portions 8 and 11 thereof outermost, and the portion 11 extending along the outer faces of the sides. Through the 15 portion 11 at suitable distances apart are driven rivets 12 which act to connect the fixture firmly to the sides.

In the bottom of the groove formed by the portions 8, 9, and 10 of the metal fixture 20 is disposed a strip of suitable material, such as felt 13, the said strip being connected to the member 9 by glue, or other suitable adhesive substance.

It will of course be understood that the 25 groove is a continuous groove extending along the side edges and the end edges, and that the felt strip is disposed in the bottom of the entire groove.

From the foregoing description it will be 30 seen that when the drawer section and the wardrobe section are brought together to closing position, the edges of the sides of the drawer section will enter the groove and bear against the felt strip disposed in said 35 groove. The groove, therefore, not only provides a retaining pocket for the felt strip, but furthermore as the walls of the groove bear against the opposite faces of the sides of the wardrobe section, they necessarily hold said sides firmly in closing 40 position, so that not only is a tight and secure joint formed, but also the two sections of the trunk are prevented from wabbling or moving one upon the other.

45 The particular style of wardrobe trunk in connection with which I have shown my improvements is one employing a corner construction similar to that disclosed in my application for Letters Patent filed June 12, 50 1915, Serial No. 33,696 and also disclosed in my application for Letters Patent filed June 12, 1915, Serial No. 33,697, which eventuated into Patent No. 1,235,948. The corner construction covered in said applications for 55 patents, and also illustrated in the present application, is one wherein the edges of the side pieces of each section of the trunk are separated from each other, and these separated edges are covered by a corner piece 60 bent to form an intermediate member of rounded shape, or convex on its outer surface, two legs formed by doubling the material upon itself, which legs bear against the separated edges of the sides, and terminal securing flanges. In the present ap-

plication, the intermediate rounded or convex portion of the corner construction is indicated on the drawing by the numeral 14, the two legs by the numerals 15, and the terminal securing flanges by the numeral 16. 70

In order to apply my improved joint to a trunk equipped with the corner construction above described, it is necessary, of course, in the section of the trunk which is provided with the groove, to make provision for 75 continuing the groove across or around the separated edges at the corners. At the front ends of the edges of the side pieces at the corner, where the corner construction referred to is employed, there would ordinarily be left an open space, and of course the continuity of the groove would be broken, or rather, there would be no bottom piece or support for the felt, similar to the support afforded by the bottom of the groove 80 proper. I, therefore, employ at each of these outer corners a corner fixture 17 which projects slightly beyond the edges of the sides at the corners, said projecting portions forming an outer wall for the edge of 85 the wardrobe section, when the wardrobe section is brought to a closing position. From a medial portion of the inner face of this metal fixture projects a lip which forms the support or bottom for the felt strip, 90 the same as the bottom of the groove proper. This lip, or support may be conveniently formed by providing a projection 18 from a medial point of the edge of the main portion of the corner fixture 17, said projection 95 being bent inwardly against the inner face of the metal fixture 17, and then bent at right angles, as indicated by the numeral 19, to form the lip referred to, and which lip covers over the open space which would otherwise be left at the outer ends of the corners between the legs 15—15, and which covering flange or lip forms a bottom support for the felt strip, the same as the bottom of the groove proper. 100

110 It is also necessary to apply a metal fixture at the outer ends of the corners of the sides of the wardrobe section of the trunk so as to avoid any break in the edges of the sides at these points. To this end, I provide at the outer ends of each corner, another metal fixture 21, the main portion thereof overlying the extreme end of the metallic corner device, which device, as before explained, consists of the bridging member, 115 the inwardly extending legs and the securing flanges. The metal fixture 21 is provided with a projecting portion 22 which is depressed slightly from the main portion of the fixture 21, as shown most clearly in 120 Fig. 5, so as to provide a depressed seat for the projecting edge of the corner fixture 17 of the drawer section, when the two sections are brought together to closing position. The extremity of this depressed por- 125 130

tion is bent at right angles, as indicated by the numeral 23, and this portion 23 forms the continuation of the edge at the corners, and avoids a break in the continuity of the 5 edges of the wardrobe section, so as to provide a complete or unbroken rectangular edge to fit the complete rectangular groove of the drawer section.

What I claim is:

- 10 1. In a joint construction for trunks, boxes or the like, the combination with a trunk comprising two sections, each section having projecting side pieces, said side pieces having their edges separated from 15 each other, devices disposed along the non-contacting corner edges of the sides of the two sections, said devices projecting over the space between the non-contacting edges of the sides, a valance secured to the edges 20 of the sides of one of the sections of the trunk, said valance provided with a groove, and corner fixtures at the outer ends of the corners, each corner fixture projecting outwardly to form an outer projecting wall, and also having a projecting lip which extends over and covers the space which would otherwise be left at the end of the bridging member, said lip thereby forming a continuation of the bottom of the groove of the 25 valance.
- 30 2. In a joint construction for trunks, boxes or the like, the combination with a

trunk comprising two sections, each section having projecting side members, said side members at their edges separated from each 35 other, devices disposed along the non-contacting edges of the sides of the two sections, each device bridging over the space formed by the non-contacting edges of the sides, a valance secured to the edges of the sides 40 of one of the sections of the trunk, said valance provided with a groove, a corner fixture at the outer ends of the corners of the sides of the section of the trunk edge which is provided with a valance, said corner 45 fixture projecting outwardly to form an outer projecting wall, and also having a projecting lip which extends over and covers the space which would otherwise be left at the end of the bridging corner device, and thereby forms a continuation of the bottom 50 of the groove of the valance, and corner fixtures at the outer ends of the corners of the other section of the trunk, each of said corner fixtures provided with a projection, 55 which projection is bent at an angle to form a member at the corner which completes the continuity of the edge.

In testimony whereof, I affix my signature, in presence of two witnesses.

GEORGE HENRY WHEARY.

Witnesses:

ANNA M. NELSON,
EMMA RASMUSSEN.
